UNITED STATES PATENT OFFICE

1,929,133

WRENCH

James L. Worth, Canyon City, Oreg.

Application September 20, 1932
Serial No. 634,061

1 Claim. (Cl. 81—165)

This invention appertains to new and useful improvements in tools and more particularly to a novel wrench.

The principal object of this invention is to provide a wrench of the single handle type and the principal object of the invention is to provide a wrench constructed in such a manner as to cause a pivoting of the handle when an object is being gripped, to the end that the jaws of the wrench will not slip off of the object, thus eliminating not only bother, but injury to the hand in knocking against adjacent objects when working in close quarters.

Other important objects and advantages of the invention will become apparent to the reader of the following specification.

In the drawings:—

Figure 1 represents a side elevational view of the wrench.

Fig. 2 represents a top plan view of the wrench.

Fig. 3 represents a fragmentary longitudinal sectional view through the wrench.

Fig. 4 represents a sectional view taken substantially on line 4—4 of Fig. 3.

Fig. 5 represents a front end elevational view of the wrench.

Fig. 6 represents a perspective view of the swingable jaw.

Referring to the drawings wherein like numerals designate like parts, numeral 5 represents the slidable jaw, while numeral 6 represents the swingable jaw, in contra-distinction to conventional wrenches which involve usually a stationary jaw and a slidable jaw.

In carrying out the present invention further, it can be seen that numeral 7 represents the handle which is bifurcated at its forward end as at 8 to receive the rectangular-shaped frame 9, the frame being swingably connected to the handle 7 at said bifurcated end by the pin 10.

The frame 9 adjacent the bifurcated end of the handle 7 is provided with a shoulder 11, while the crotch portion of the bifurcated end of the handle 7 is provided with a recess 12 for receiving one end portion of the compressible coiled spring 13, the other end of the spring bearing against the aforementioned shoulder 11, for obviously maintaining the frame 9 in the position shown in Fig. 3. The leg portions of the bifurcations of the handle 7 are cut away as at 14 to receive the butt end of the aforementioned swingable jaw 6. As is clearly shown in Figs. 3 and 6, the jaw 6 is of substantially U-shape, the inner side of the bight portion being beveled as at 15 by engagement with the corresponding beveled portion of the frame 9, while the outer portion of the bight of the jaw 6 is beveled as at 16.

The leg portions of the jaw 6 are provided with openings 17 for receiving the pin 18 passing

through the upper portion of the frame 9 in the manner shown in Fig. 3.

Slidable through a longitudinal opening in the frame 9 is the rack 19 carrying the jaw 5 which is rigidly secured to the rack. A pin 20 extends into the frame and carries the worm 21 which is in mesh with the rack 19.

Now referring to the jaw 6, it can be seen that the same is recessed as at 22 while the corresponding portion of the frame 9 is recessed and projecting into these recessed portions of the frame and jaw are the end portions of the compressible spring 23.

It can now be seen in Fig. 1, that by swinging downwardly on the handle 7, with an object between the jaws 5 and 6, the extensions 24 on the bifurcated end of the handle 7 will ride up against the leg portions of the jaw 6 and rock the same inwardly into a more snug contact with the object between the jaws. In other words, with the conventional wrench, it is sometimes possible for the slidable jaw to yield permitting the wrench jaw to rotate on the object, but this is entirely eliminated with the use of the present tool, which allows the jaws to tighten all the more in response to pressure exerted on the handle 7.

Obviously the springs 13 and 23 serve to maintain the frame 9 and the jaw 6 respectively in a normal position for receiving an object.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

A wrench of the character described comprising a handle, a frame, a worm mounted in the frame for rotation, a rack slidable on the frame, a head on one end of the frame, said worm meshing with and adapted to operate the said rack, said handle being pivotally secured to the frame, a slide jaw carried by the rack, said head being beveled, a swingable jaw having a pair of side members, a pivotal connection between the swingable jaw and the head, abuttingable construction between the side members and the handle, said swingable jaw being beveled to engage with the beveled portion of the head, and a spring interposed between the beveled side portions of the head and swingable jaw.

JAMES L. WORTH.
